UNITED STATES PATENT OFFICE.

HENRY W. BROCK, OF DENVER, COLORADO.

RAILWAY SIGNALING SYSTEM.

Application filed November 24, 1923. Serial No. 676,839.

To all whom it may concern:

Be it known that I, HENRY W. BROCK, a citizen of the United States, residing at Denver, in the county of Denver and State 5 of Colorado, have invented certain new and useful Improvements in Railway Signaling Systems, of which the following is a specification.

My invention relates to railway signaling systems and more particularly to danger signals of the type used to warn engineers of approaching trains of the unsound condition of a railway bridge structure spanning a river, creek, draw or other water- 15 course.

It is a well established fact that the first action of the water during a flood or washout in a stream or in the normally dry bed thereof, is to erode the upper stratum of the 20 bed thereby weakening the supports of a railway built across the stream. After an occurrence of this kind, the track of the railway bridge may remain in its normal aligned and horizontal condition and thus 25 appear perfectly safe to the eye of the driver of an approaching engine until the train passing across the inadequately supported structure causes the bridge to collapse with inevitably disastrous results.

It is the object of my invention to avoid 30 accidents of the above described nature by the provision of a simple though highly effective and dependable signaling system which by visual or audible means, gives 35 warning to engineers of trains approaching a stream or draw from either side, that by a washout of all or part of the bed thereof, the railway structure built across the stream has been rendered unsafe and is liable to 40 break under the weight of the engine or its train.

With the above and other objects in view as will fully appear in the course of the 45 following description, my invention comprises a mechanism which is actuated by the removal of part or all of the upper stratum of a creek or river bed, to operate signal devices placed at opposite sides of the water course and at a sufficient distance 50 from the same to permit of an approaching train being brought to a full stop before it reaches the bridge structure.

The signal devices may operate either mechanically or electrically; they can be 55 equipped with lamps so as to be visible at

night or they may consist of a siren, gong, railway torpedo or other loud sounding appliance.

An embodiment of my invention has been illustrated in the accompanying drawings in 60 which like characters of reference designate corresponding parts throughout the several views and in which—

Figure 1 represents a plan view of a railway structure across a water course, to 65 which my signaling system is applied;

Figure 2, a partially sectional side elevation of the same;

Figure 3, an enlarged sectional elevation of the element of the system installed in the 70 banks or fills of the watercourse;

Figure 4, an enlarged, cross-section of the bridge structure along the line 4—4, Figure 2;

Figure 5, a similar section taken on the 75 line 5—5, Figure 2;

Figure 6, a sectional elevation of a semaphore adapted for use in the system;

Figure 7, a section along the line 7—7, Figure 6; and

Figure 8, an enlarged fragmentary sectional elevation of the cable which constitutes an element of the signal-actuating mechanism, and the supporting and suspension devices associated therewith. 85

Referring more specifically to the drawings, the reference character 5 designates the bed of a creek, river, draw or other watercourse, and 6 the fills or embankments at the sides thereof. 90

The railway bridge 7 which spans the bed, as shown in the drawings, consists of a plurality of piers 8 usually made of cement or cemented stone, trestles 9 erected on the piers, stringers 10 supported on the trestles 95 and rails 12 which are laid upon cross ties 13.

My signaling system as applied to a bridge of the above described construction, comprises one or more flexible cables 14 100 preferably made of wire, which are supported below and in paralleled relation to the structure upon sheaves or pulleys 15.

The cable connects at its ends with signaling devices 16 installed at opposite sides 105 of the watercourse, the construction of which will hereinafter be described, and where the cable or cables pass underground they are encased in tubes or conduits 17.

Suspended from the cable or cables pref- 110

erably between pairs of its supporting sheaves, are a plurality of heavy weights 18 normally supported upon the bed of the watercourse in close proximity to the piers 5 or other foundation of the railway bridge.

In the construction shown in the drawings, the weights are slidably disposed in vertical bores 19 of the piers and they are suspended from the cable or cables by means 10 of slender rods or wires 20. To prevent the weights from pressing into the river bed should the latter be of soft formation, they may be placed upon seats 21 preferably made of cement, which are inserted through 15 the bores of the piers.

In order to prevent the water in the creek or river from entering the bores of the piers, flanged tubes 22 through which the rods or wires 20 of the weights are loosely 20 drawn, are fastened upon the piers above their bores, in water-tight connection with the surface with which their flanges engage, the tubes being of sufficient height to extend above the water-level.

25 A plurality of weights 23 similar to those hereinbefore described, are embedded in the fills or embankments of the river bed in the vicinity of their surface, and pulleys 24 upon which the respective cables 14 are supported, are mounted in box-like enlargements 25 of the underground conduits 17, which are provided with downwardly extending tubes 26 to encase the slender connections 27 by means of which the weights 30 23 are suspended from the cables.

The weights embedded in the embankment are of compact shape in contradistinction to the weights in the piers which are of elongated form.

40 The cables 14 are preferably made in sections connected by turn buckles 28 for their relative adjustment to regulate the tension of the cables.

The signaling devices 16 hereinbefore referred to must necessarily be of a character to effectively operate by a slight pull on the cable or cables when one or more of the weights go down by reason of the removal of the part of the bed upon which they are 45 normally supported. A construction of this character has been illustrated in Figures 6 and 7 of the drawings, in which 29 designates a pedestal which supports a rotary lamp or other signal 30.

55 The signal is mounted at the upper end of a shaft 31 passing through the pedestal, and the lower end of this shaft extends into a subterranean chamber 32 which connects with the conduit 17 of the respective cable 60 14 as shown in Figure 7.

The end of the cable is fastened at the periphery of a winding drum 33 on a shaft 34 rotatably mounted in bearings in the chamber. The shaft is provided with a 65 crank 35 from which is suspended a trig-

ger-member 36 the lower end of which rests normally against a shoulder 37 in the bottom of the chamber.

The trigger normally restrains the rotary movement of the signal by engagement with a lever-arm 38 at the lower end of the shaft 31, a coiled spring 39 having been provided to effect said rotary movement when the lever arm is released.

70 It will be understood that when a number of cables 14 are applied to a bridge structure, they are united into one element which connects with the semaphore, as indicated in Figure 1 in which the different conduits 17 through which the cables pass are 75 by means of branches 40 connected to single conduits 41 connected with the underground chambers of the semaphores.

80 In the operation of my invention, the downward movement of any one of the weights when the portion of the ground upon which it normally rests, is eroded by the action of the water in case of a wash-out, will result in a pull on the respective cable.

85 The lengthwise movement of the cable produces a partial rotation of the drum of the signaling device to which its end is connected, and the consequent upward manner of the trigger releases the arm on the shaft 90 31 which under the influence of the spring 39 imparts a rotary motion to the signal 30 mounted at its upper end.

95 It will thus be apparent that the slightest disturbance of the ground upon which the railway structure is supported either in the watercourse or in the fills or embankments at the sides thereof, will result in the operation of the signal devices and that in consequence, warning is given of the unsafe condition of the structure even though in appearance it is in its normal state.

100 The signaling device shown in the drawings and hereinabove described, is merely 105 illustrative of one of many constructions 110 that may be employed in connection with the actuating elements of my invention, and I desire it understood that variations in the construction of the signal devices as well as in the arrangement of the weights 115 and cables on the bridge structure, may be resorted to within the spirit and scope of my invention as defined in the hereunto appended claims.

120 What I claim and desire to secure by Letters Patent is:

1. In a railway signaling system, the combination with a railway track, of a support therefor, having a vertical bore, a weight in said bore resting on ground beneath the support, a signaling device, and means for the operation of said device by downward movement of the weight.

125 2. In a railway signaling system, the combination with a railway track, of a sup- 130

port therefor, having a vertical bore, a weight in said bore resting on ground beneath the support, means closing the upper end of the bore against the inflow of water, a signaling device, and means for the operation of said device by downward movement of the weight.

3. In a railway signaling system, the combination with a railway track, of a support therefor, having a vertical bore, a signaling device, a movably supported cable for the operation of the device, and a weight in said bore normally resting on ground beneath the support and suspended from the cable.

4. In a railway signaling system, the combination with a railway track, of a support therefor, having a vertical bore, a signaling device, a movably supported cable for the operation of the device, a flanged tube on the support in alignment with its bore, a weight normally resting on ground beneath the bore, and a connection between the weight and the cable, passing through the tube.

5. In a railway signaling system, the combination with a railway track and means for supporting it on the ground, of a signaling device including a signal movable to a danger-indicating position, a trigger normally restraining the signal, a lengthwise movable cable for the withdrawal of the trigger and a weight normally resting on ground beneath the support, and a connection to effect an operative movement of the cable by downward movement of the weight.

6. In a railway signaling system, the combination with a railway track, and means

for supporting it over a river bed or the like, of a signaling device, an element supported for longitudinal movement in operative connection with the device, and a movably suspended weight for the actuation of said element, normally resting on the ground beneath said supporting means.

7. In a railway signaling system, the combination with a railway track, and means for supporting it over a river bed or the like, of a signaling device, an element extending across the river bed and supported for longitudinal movement in operative connection with the device, and a movably suspended weight for the actuation of said element normally resting on the ground beneath said supporting means.

8. In a railway signaling system, the combination with a railway track and means for its support in an elevated position above a ground-surface, of a signaling device, an element supported for longitudinal movement in operative connection with the device, and a movably suspended weight for the actuation of said element, normally resting on the ground beneath said supporting means.

9. In a railway signaling system, the combination with a railway track and a pier for its support over a river bed or the like, of a signaling device, an element supported for longitudinal movement in operative connection with the device, and a movably suspended weight for the actuation of said element, normally resting on the ground beneath said pier.

In testimony where I have affixed my signature.

HENRY W. BROCK.
